US00D461175S

(12) **United States Design Patent**
Yokota

(10) Patent No.: **US D461,175 S**
(45) Date of Patent: **** Aug. 6, 2002**

(54) **COMBINED WIRELESS TELEPHONE AND
PLAYER/RECORDED**

(75) Inventor: **Hiroaki Yokota, Tokyo (JP)**

(73) Assignee: **Sony Corporation, Tokyo (JP)**

(**) Term: **14 Years**

(21) Appl. No.: **29/148,251**

(22) Filed: **Sep. 18, 2001**

(51) LOC (7) Cl. **14-03**

(52) U.S. Cl. **D14/144; D14/138; D14/168;
D14/341**

(58) Field of Search **D14/137, 138,
D14/218, 147-148, 247-248, 336, 496,
144, 167, 168, 341-347, 163-165; 379/433.01-433.13,
419, 434, 428.01-428.04, 420.01-420.04,
440; 455/550-575, 90; D13/168; D18/2,**

(57) **CLAIM**

The ornamental design for a combined wireless telephone and player/recorder, as shown and described.

DESCRIPTION

FIG. 1 is a perspective view of a combined wireless telephone and player/recorder showing my new design;
FIG. 2 is a front elevational view thereof;
FIG. 3 is a rear elevational view thereof;
FIG. 4 is a left side elevational view thereof;
FIG. 5 is a right side elevational view thereof;
FIG. 6 is a top plan view thereof; and,
FIG. 7 is a bottom plan view thereof.
